UNITED STATES PATENT OFFICE.

WILLIAM F. DANA AND HENDERSON W. KNOTT, OF NEW YORK, N. Y.

ELECTRIC RHEOSTAT.

No. 841,232.

Specification of Letters Patent.

Patented Jan. 15, 1907.

Application filed July 26, 1905. Serial No. 271,388.

To all whom it may concern:

Be it known that we, WILLIAM F. DANA, a citizen of the United States, and HENDERSON W. KNOTT, a subject of the King of Great Britain and Ireland, residing at New York city, in the county of New York and State of New York, have invented a new and useful Improvement in Electric Rheostats, of which the following is a specification.

10 Our invention relates to rheostats in which the electric current is gradually increased from a desired minimum to a desired maximum by the means of a series of graduated resistances. In such rheostats now in use the contact between the switch and the several resistances is usually effected by intervening wires duly attached and insulated, and the rheostat becomes in consequence cumbrous and complicated. The object of 15 our improvement is to construct a rheostat which shall be simple and compact in form.

Our method is to provide strips or buttons of gradually-increasing degrees of resistance and to arrange them consecutively in columnar form with an alternating series of metallic contact-plates. These resistances are composed of graphite and clay (preferably German clay) powdered and mixed together, pressed into the form of buttons of 20 similar design and shape, and baked. The graphite and clay when thus baked is brittle and inclined to crack and break off in case the rheostat sustains a jar or shock. It is therefore essential that the buttons be partially inclosed. This is effected by either bending the projecting edges of the metallic contact-plates over against the resistance-buttons, or preferably by causing their 25 surfaces to be hollowed out or recessed, so that

40 the contact-plates assume a cup-like shape and are thus adapted to receive, surround, and bind in the buttons. Because of the brittle character of the baked graphite and clay and of its naturally irregular cleavage it is 45 practically impossible to effect a complete and perfect contact between the surfaces of the buttons and the surfaces of the metal plates without some intervening medium.

To overcome this difficulty, we introduce between them a graphitic paste, whose conductivity is similar to that of the metal plates, and with it we securely cement those surfaces together in close and uniform contact.

55 The method above described permits the

arrangement of separate resistances in a simple, secure, and compact form, such as is not possible in rheostats where connections are made by wire, and it thereby dispenses with the use of wire and with the expense of 60 wiring between the resistances and contact-pieces.

Our invention is illustrated in the accompanying drawings, in which—

Figure 1 is a front view of our improvement complete and ready to be inserted in a rheostat-frame. Fig. 2 is a detailed sectional view of the same, showing the method of connecting the resistance-buttons to the contact-plates in form of a column and of insulating them from their common support. Figs. 3 and 4 illustrate one of said plates and one of said resistance-buttons, respectively.

Similar letters refer to similar parts throughout the several views.

75 The buttons A are composed of graphite and clay, as above described. They are similar in design and form and are of different and graduated degrees of resistance, the degree of resistance being in inverse proportion to the amount of graphite present in the mixture. The buttons A are consecutively arranged upon and in alternation with the contact-plates B. These plates are made of metal and project beyond the edges of the 80 buttons A. They are similar in form and are preferably flattened at one edge b. The surfaces of the plates B are hollowed out or recessed, so as to receive the buttons A, which fit in them closely. These recesses 85 are of sufficient depth to bind the buttons in and to prevent them from breaking or crumbling in case the rheostat suffers a violent shock or jar.

90 As above set forth, it is practically impossible without a medium to effect a perfect contact between the surfaces of the buttons and the recessed surfaces of the contact-plates. To fill up the interstices and spaces between the adjacent surfaces and to cement 95 them together, we have provided a paste of high conductivity. This paste is composed of powdered graphite, pure carbon-dust, and gum-tragicum mixed together in the proportions of six, three, and one, respectively. 100 Sufficient water is added to secure to the mixture the proper consistency of paste. In preparing the above composition the graphite must be first freed from all gaseous elements 105 by subjecting it to intense heat.

The buttons A and the plates B are placed one upon the other and cemented together in the form of a column and are secured in position by a bolt C passing through them all 5 and fastened into the frame of the rheostat. The bolt C is furnished at its ends with the nuts M and M'. The buttons A and the contact-plates B are insulated from the bolt C and from its said nuts by the insulating material D. The flattened edges b of the contact-plates B are arranged in the same plane; and thus present an even contact-surface, over 10 and upon which any contact-switch with which rheostats are commonly furnished 15 may be swept or manipulated, thus bringing the different and graduated resistance-buttons consecutively into circuit.

We are aware that neither a series of resistances with interposed metallic contacts 20 nor a switch adapted to be manipulated in the path of such contacts are new in themselves, and we make no claim hereinafter broad enough to include such series or such switch.

25 What we claim as our invention, and desire to secure by Letters Patent, is—

1. A rheostat comprising a series of resistances composed of graphite and clay, alternating with interposed metallic contact- 30 plates, the surfaces of which are sufficiently recessed to closely receive and rigidly hold said resistances in superficial contact, and to protect them from shock or other external injury, substantially as described.

2. A rheostat whose resistances are composed of graphite and clay mixed and formed into buttons of similar form, and cemented in close superficial contact to interposing metallic contact-plates by a graphitic paste of high conductivity, substantially as described. 35

3. The combination, in a rheostat, of graphite and clay resistance-buttons and of interposed metallic contact-plates, alternating therewith and completely united thereto at their respective surfaces by a graphitic paste, 40 composed of powdered graphite, pure carbon-dust, gum-tragicum, and water mixed together, substantially as described.

4. A rheostat comprising the resistance-buttons A, similar in form and of graduated 45 degrees of resistance, rigidly held in alternating series with and protected by the recessed contact-plates B and united to them in complete contact at their respective surfaces by a graphitic paste of high conductivity, all arranged in form of a column and so adapted that a contact-switch may be manipulated in the path of said contact-plates, substantially as described.

In witness whereof we have signed our 60 names to this specification in the presence of two subscribing witnesses.
